FOREIGN PATENT DOCUMENTS

WO 2008/148748 A1 12/2008

Primary Examiner — Thomas Johannes

Assistant Examiner — Shawn T Gingrich

(74) Attorney, Agent, or Firm — Banner & Witcoff, Ltd.

(57) **CLAIM**

The ornamental design for connector shell, as shown and described.

DESCRIPTION

FIG. 1 is a front top perspective view of connector shell showing our new design;

FIG. 2 is a top view thereof;

FIG. 3 is a bottom view thereof;

FIG. 4 is a left side view thereof;

FIG. 5 is a right side view thereof;

FIG. 6 is a rear view thereof;

FIG. 7 is a front view thereof; and,

FIG. 8 is a front bottom perspective view.

The broken lines in the drawings illustrate portions of the connector shell that form no part of the claimed design.

1 Claim, 8 Drawing Sheets(56)
